UNITED STATES PATENT OFFICE.

ISABEL HARPER HOLMES, OF TORONTO, CANADA.

UMBRELLA-HOLDER.

SPECIFICATION forming part of Letters Patent No. 634,526, dated October 10, 1899.

Application filed May 2, 1898. Serial No. 679,467. (No model.)

To all whom it may concern:

Be it known that I, ISABEL HARPER HOLMES, gentlewoman, of the city of Toronto, in the county of York, in the Province of Ontario, 5 Canada, have invented certain new and useful Improvements in Umbrella-Holders, of which the following is a specification.

My invention relates to improvements in umbrella-holders; and the object of the invention is to design a simple, efficient, and handsome holder for umbrellas which when not in use will automatically recede from its projecting position when in use; and it consists, essentially, of a holding-lever plate 15 provided, preferably, with two jaws pivotally held on a suitable bracket, the shorter end of the lever having connected to it by a suitable chain or cord a weight designed to normally hold the jaws out of the way, as hereinafter 20 more particularly explained.

Figure 1 is a perspective view of an umbrella-holder designed to be pivotally held in its closed position under a ledge to a counter or other suitable constructional portion of an 25 apartment, hall, or shop. Fig. 2 is a view showing the adaptability of my umbrella-holder when applied to the side of a counter. Fig. 3 is a detail showing the bracket and holding-jaws, the plate forming part of the 30 jaws being broken away to exhibit the construction of the bracket and the position thereof when adapted as shown in Fig. 1. Fig. 4 is a detail of my umbrella-holder, showing the plate of the jaw broken away to exhibit 35 the construction and position of the bracket when adapted as shown in Fig. 2. Fig. 5 is a detail of the plate and jaws-forming part thereof.

In the drawings like letters and numerals of 40 reference indicate corresponding parts in each figure.

A is the counter, and B a broad overhanging ledge.

In Figs. 1, 3, and 5, C is a plate provided 45 with the curvulate fingers c, c', and c''. The curvulate fingers c and c' form the jaws of a recess of substantially the same width throughout. The finger c' is curved to form a flaring opening with the finger c and is 50 stamped with the recess c³, so as to cause it to assume a semicircular form in cross-section, and thereby give it a resilient prop-

erty. The finger c² together with the finger c' form jaws with a contracted entrance, the width between the jaws being substantially 55 equal throughout. The width between the fingers c' and c² is, however, much less than the width between the fingers c and c', as such is intended to receive much smaller umbrellas than that of the latter space. In fact, it is 60 more adapted to receive a lady's umbrella than a gentleman's.

The entrance to the space between the jaws is contracted, and consequently when the umbrella is forced in through the entrance 65 in either case the finger c' springs back to allow of the entrance of the handle of the umbrella and yet will not permit of the umbrella falling out again, but will permit of it being forced out by a slight pressure.

It will be noticed that the rear end of the 70 jaw-plate C is provided with a circular opening C², having diametrically-situated notches C³, substantially parallel with the ends of the fingers c and c'. It will also be noticed that 75 at one side of the portion C' of the plate C is formed a depressed eye-lug C⁴.

D is an angular bracket, one angular end of which is provided with the central hole d, a raised stamped-up boss d' surrounding the 80 same, and a raised stamped-up boss d² concentric to the boss d'.

d³ is an eye formed or stamped out at the angle of the bracket at the outside. The opposite end of the bracket to that in which 85 the hole d is formed is bent also in the shape of a right angle, the end projecting at each side beyond the side edges of the bracket, so as to form an end bar d⁴.

It will be seen that the circular opening C² 90 fits around the circular boss d' of the bracket D and that the edge of the plate around the opening rests upon the circular boss d² above the level of the remaining portion of this side of the bracket.

I provide a screw 2 to secure the bracket in 95 position underneath the ledge, and it will therefore be seen that when secured the boss d' forms the pivot-point upon which the jaw-plate turns. On the lug C⁴ is connected, preferably by a fine chain or cord f, a circular weight F, such chain extending from the eye-lug C⁴ through the guiding-eye d³ at the 100 outer angle of the bracket and the hole d⁵ in

the end of the bracket. It will now be seen that the normal tendency of the weight F, which is much heavier than the plate C, is to hold the plate C so that the eye-lug C⁴ is opposite the lug d³ and the umbrella-holder in the position shown in the dotted lines in Fig. 1. The side of one of the fingers is arranged so as to project slightly beyond the edge of the ledge B. When, therefore, it is desired to pull out the jaws to put an umbrella in, as indicated in this figure, it is simply necessary to pull out the finger c² of the jaw-plate C until the plate assumes the position shown in full lines in Fig. 2, when the umbrella may be inserted between the fingers of either jaw. If inserted between the fingers c and c², the finger c² of the other jaw may be utilized to hang a parcel on or the other jaw itself may be used to receive another umbrella. The weight and position of the umbrella of course causes sufficient friction to prevent the jaw-plate from assuming its normal position under the ledge; but immediately the umbrella is removed the eye-lug C⁴ is pulled upon by the weight, so as to swing the jaw-plate back into the normal position shown in dotted lines. The above is the position which I preferably provide for my holder when the ledge is sufficiently broad to accommodate the width of the jaw-plate underneath the same. In case where the ledge B is of a lesser width, as shown in Fig. 2, I support the jaw-plate upon the opposite end of the bracket, as shown in this figure, in which figure it will be noticed that the notches C³ on the sides of the opening fit the sides of the bracket closely and the plate at the side of the notches rests upon the laterally-extending end bar d⁴, which therefore forms the pivot-point for the jaw-plate. The bracket itself to the inside of the end bar d⁴ forms a stop for the inner end of the plate, so that the jaw-plate will not come down below the horizontal. The bracket is secured in position to the side counter or wall by a screw 2. The weight is suspended by means of the cord f from the center of the back of the jaw-plate—that is, at the rear of the circular opening C². The normal tendency of the weight F is to throw the jaw-plate, which is really a lever of exactly the same class as before described in Fig. 1, into the position shown in dotted lines in Fig. 2, which position is the normal position. When thrown down into the position as shown in full lines in this figure, the weight of the parasol or umbrella is sufficient to counterbalance the weight F, and thereby hold the umbrella from falling. As soon as the umbrella is removed from the jaws of course the jaw-plate will assume the position shown in Fig. 2.

It will be noticed from this specification how simply and effectually I have provided a bracket and a jaw to be used in connection

therewith, which may be adaptable either to an overhanging ledge or to the side of a wall or counter, and this, too, without the necessity of providing any extra portions. All the parts may be stamped out of sheet metal of sufficient thickness, and all it is necessary to do to place the umbrella-holder in the requisite position is to change the position of the bracket in relation to the jaw-plate.

What I claim as my invention is—

1. An umbrella-holder comprising a bracket adapted to be secured to either a vertical or horizontal support, a plate having spring-arms arranged to engage an umbrella or the like, said plate being detachably hinged to said bracket means whereby said plate can swing either horizontally or vertically, and a counterbalance connected to said plate, substantially as described.

2. In an umbrella-holder, the combination with the jaw-plate, circular opening at the rear end thereof provided with diametrically-situated notches and the weight connected by a chain to the rear end of the jaw-plate, of the angle-bracket designed to fit into the notches and provided with an angled outer end, the extreme end of which forms a cross-bar extending underneath the plate beyond the edge of the notches as and for the purpose specified.

3. In an umbrella-holder, the combination with the jaw-plate circular opening at the rear end thereof provided with diametrically-situated notches and the weight connected by a chain to the rear end of the jaw-plate, of the angle-bracket designed to fit into the notches and provided with an angled outer end, the extreme end of which forms a cross-bar extending underneath the plate beyond the edge of the notches and the circular boss-shaped opposite end of the bracket provided with the central hole and screw to secure such end in position as and for the purpose specified.

4. In an umbrella-holder, the combination with the jaw-plate provided with a circular opening and laterally-extending eye-lug, of the bracket provided with circular bosses upon which the circular opening at the rear end of the jaw is designed to swing, a circular hole and screw extending through such hole into the counter to hold the bracket in position, an eye formed in the bracket, a chain connected to the eye-lug and extending through the eye and through a hole in the end of the bracket and a weight suitably connected to the end of the chain as and for the purpose specified.
